UNITED STATES PATENT OFFICE

149,241

DESIGN FOR A BROOCH OR SIMILAR ARTICLE

Humbert Armao, Providence, R. I.

Application March 4, 1947, Serial No. 137,332

Term of patent 3½ years

(Cl. D45—19)

To all whom it may concern:

Be it known that I, Humbert Armao, a citizen of the United States, residing at Providence, in the county of Providence and State of Rhode Island, have invented a new, original, and ornamental Design for a Brooch or Similar Article, of which the following is a specification, reference being had to the accompanying drawing, forming part thereof.

I claim:

The ornamental design for a brooch or similar article as shown.

HUMBERT ARMAO.
